LIQUID SOAP MIXING DEVICE

Edward J. McGrail, Pittsburgh, Pa., assignor to
S. Strunz & Sons, Inc., Pittsburgh, Pa., a cor-
poration of Pennsylvania

Application December 29, 1934, Serial No. 759,721

1 Claim. (Cl. 299—84)

My invention relates to apparatus for mixing liquid soap and water and for discharging it in a directed stream under pressure and for an apparatus wherein the flowing stream of water with 5 which the soap is to be mixed operates to draw the liquid soap into the stream and effect the mixing of the soap and water.

In view of the widespread and extensive use 10 of a mixture of soap and water in automobile establishments and other industrial enterprises, it is important to provide apparatus for mixing the soap and water in the exact desired proportion without supervision thereof on the part of the user. It is undesirable to allow the unskilled 15 user to use his own judgment in mixing the soap and water since too large a proportion of soap will be not only wasteful but also possibly harmful and too small a proportion of soap will not permit an efficient and workmanlike job to be 20 performed.

The present invention provides an arrangement wherein the soap and water are automatically mixed in predetermined proportions and without the loss of any time, whereby the soap 25 may be most efficiently and economically used. Moreover, the present invention provides an arrangement wherein the liquid soap is prevented from caking, air-hardening, or otherwise solidifying in the various parts of the apparatus so 30 that the apparatus may be shut down over night, over the week-end, or for indefinite periods without accumulation of soap forming any part thereof where it would interfere with the proper functioning of the device.

35 The invention also provides a restricted discharge orifice for the mixture of the liquid soap and water so that the mixture discharged into a bucket or other container may be thoroughly mixed and cause the formation of an appreciable 40 amount of suds above the surface of the mixture.

The invention may be readily understood by 45 reference to the accompanying drawing, in which the single figure discloses, more or less diagrammatically, a view partly in section and partly in elevation of one embodiment of my invention.

In the drawing, 2 designates a water supply 50 line, to which is connected an aspirating device or ejector 3 by means of an elbow 4. The aspirating device may be of any one of a number of standard makes or of any preferred construction and comprising the usual elements more or less conventionally shown, these being a cone-shaped nozzle or jet 5, the apex of which is directed into the open end of a venturi 6, there being an an- 55 nular suction chamber 7. The venturi leads into

a discharge pipe 8 to the end of which is fastened a control valve 9, below which is a discharge tube or spout 10, the end of which is restricted so as to cause the mixture to be discharged in a compact stream. Communicating 5 with the suction chamber 7 of the aspirator 3 is a soap intake pipe 11 having an extension 12, which extends into the soap container or reservoir 13. The extension 12, which extends almost to the bottom of the container 13, is provided 10 at its lower end with a check valve 14, which allows a liquid soap to pass upwardly through pipe 12 but which prevents a back flow of any liquid. Pipe 11 has a regulating or needle valve 15 preferably located adjacent the point where 15 pipe 11 is connected to the aspirator 3. By means of valve 15, the amount of soap which can be drawn into the aspirator can be very accurately controlled. To prevent unauthorized tampering with the mixture, once the valve is properly adjusted the valve handle 16 may be removed or a wrench may be used to set the valve in place of the handle 16.

In the operation of the device, the opening of 25 valve 9 causes water to flow from the supply line 2, this being connected to any source of water supply. As soon as the water starts to flow, liquid soap will be drawn from the reservoir 13 through tube 12 and discharged into the suction 30 space 7, where it will be drawn into the stream 35 of water.

While the stream of water is flowing, the valve 15 is adjusted to allow the desired amount of soap to be drawn into the water stream. The valve 15 once adjusted need not be again manipulated unless and until it is desired to change the proportion of soap in the mixture issuing from orifice 10. Since the valve 9 is below the aspirator, it is apparent that the pipe 8 and the aspirator will be always filled with water and 40 the soap intake pipe will be always filled with soap or water or a mixture thereof whether or not water is actually passing through the apparatus, the check valve 14 effectively preventing any back-flow of soap. The end of pipe 11 where 45 it discharges into the suction chamber 7, as well as the valve 15, is thus always protected from at atmosphere by means of the water seal in pipe 2, elbow 4, and pipe 8. This prevents the discharge end of pipe 11 and valve 15 from becoming encrusted with dried or partly congealed soap, so that once the valve 15 is adjusted the amount of soap drawn into the water passing through the apparatus will always remain constant. 50 55

It is thus seen that I have provided by my invention a simple apparatus for mixing liquid soap with water in any desired predetermined proportion and one which is extremely simple and requires, after once being adjusted, no further manipulation by unskilled or unauthorized workmen, and no time is lost in mixing the soap and water, as the mixture of the desired proportion may be drawn just as rapidly as the plain water would flow from the usual supply tap. By operation of valve 9, any desired amount of a predetermined mixture of liquid soap and water can be readily obtained. Due to the restriction of orifice 10, the water is discharged into the receptacle in such a manner that heavy suds will be formed in the bucket or other receptacle and a further mingling and agitation of the soap and water will be effected.

I have illustrated and described the present preferred embodiment of my invention, but it will be understood that the invention is not one lim-

ited thereto but may be otherwise embodied within the scope of the following claim.

I claim:

A device for mixing liquid soap and water in predetermined proportions, comprising a soap discharge tube for insertion in a container, a water supply pipe, a union between the water supply pipe and the upper end of said soap discharge tube, said union having an interior jet arrangement such that a flow of water through 10 the union induces liquid soap to be drawn from the soap discharge tube into the water, a discharge member on the outlet side of the union having a manually operable valve for controlling the flow of water and soap mixture from the 15 union, the arrangement being such that when the valve is closed water remains in the union to prevent the congealing of the liquid soap, and a check valve in the soap tube to prevent the flow of water from the union back through said tube. 20

EDWARD J. McGRAEL.
